UNITED STATES PATENT OFFICE.

BENJAMIN H. WITHERBEE, OF RED CLOUD, NEBRASKA.

LEVER.

1,156,961.

Specification of Letters Patent.

Patented Oct. 19, 1915.

Application filed December 30, 1913. Serial No. 809,511.

To all whom it may concern:

Be it known that I, BENJAMIN H. WITHERBEE, a citizen of the United States, and a resident of Red Cloud, in the county of Webster and State of Nebraska, have invented certain new and useful Improvements in Levers, of which the following is a specification, reference being had to the accompanying drawings.

10 This invention relates to certain new and useful improvements in levers, and the aim of my invention is to improve the construction and operation of that class of levers used to control by hand or otherwise, the movement of a brake beam; the mechanism to start and reverse an engine, or to reciprocate a movable member actuated by a manually operated lever.

To this end my invention consists in constructing a frame carrying a lever, the upper end of which is capable of being flexed, and which carries a detent normally in frictional engagement with an arcuate bar, with means to release said detent.

25 With these and other objects in view, the present invention consists in the combination and arrangement of parts as will be hereinafter more fully described and finally pointed out in the appended claims, it being 30 further understood that changes in the specific structure shown and described may be made within the scope of the claims, without departing from the spirit of the invention.

35 In the accompanying drawings forming a part of this specification and in which like numerals of reference indicate similar parts in the several views: Figure 1, shows a plan view of a lever constructed according to my 40 invention. Fig. 2, shows a top view with parts removed. Fig. 3, shows an edge view partly in section.

45 In my present invention I provide a lever, which is normally held in locked position, but which can be easily thrown backward or forward to any desired point, where the lever will remain locked.

In the accompanying drawings, I have shown at 1, a base member carrying the pivot 50 2. Secured to the ends of this base member 1, is a locking bar 3, with an inner edge 4, in an arc of a circle. Held pivotally upon the member 2, is a lever, the lower portion 5, of which has an opening to receive the bolt 2, while above and below the bolt 55 are the openings 6 and 5', which are adapted

to receive an operating bar connected to a brake beam, or to any other mechanism which it is desired to operate. The upper end 7, of the lever ends in a handle, while intermediate of its ends this lever is provided with a flexible part 8. In the drawings the lever is shown as made of a bar, which at the point 8, is twisted at right angles to provide a flexible or pliable part.

60 As shown in Fig. 1, the flexible part 8 is immediately below the arcuate bar 3. Secured to the lower lever part 5, is a detent 9, which has the ends 10, and 11 extending approximately at right angles to one another, and these ends 8 are normally in spring pressed or frictional engagement with the inner edge 4, of the arcuate locking bar 3.

65 As shown in Figs. 2 and 3, the lever portion 7, is arranged to slide against one face of the locking bar 3. Secured to the upper portion 7, of the lever, is a striker plate 12, having the notches 13 and 14, located adjacent to the ends 10 and 11. In order to hold the 70 upper lever end 7, to the arcuate member 3, I employ a pin 15, which is bent at right angles to slidably hold the lever to the member 3. The detent 9, is of flexible material, and in securing the same to the lever the 75 ends 10 and 11, are sprung outward so that after the detent 9, is secured the ends 10, and 11, are in spring pressed contact with the inner circular edge 4, of the member 3.

80 As shown in Fig. 1, the lever cannot be moved as if the lever should be tilted toward the member 10, this member will be more securely bound against the arcuate edge 4, while if the lever is tilted toward the member 11, this member is more securely 85 bound against the inner edge 4, so that the greater the strain upon the lever, the more firmly is the lever held.

85 In order to actuate the lever, it is merely necessary to disconnect the detent upon 90 the side toward which the lever is tilted. Should it be necessary to tilt the lever in the direction of the arrow α , the operator would merely exert sufficient pressure upon the upper end 7, to flex this end to bring the 95 notch 13 into engagement with the detent 10, which would result in this detent being released permitting the lever being tilted. The opposite detent 11, would readily slide over the inner arcuate edge 4. The notches 100 13 and 14, not only serve to engage the detents, but they also serve as a stop, limiting 105 110

the movement of the flexed end of the lever. As soon as the pressure is removed the flexed end of the lever automatically alines itself, to instantly lock the detent. The operation in a direction opposite the arrow *x*, would be exactly similar.

From the foregoing it will be seen that the lever can be locked at any desired point.

While I have shown the lever provided 10 with an integral flexible part 8, it is of course understood that the members 5 and 7, could be separate and distinct and have an interposed flexible member 8.

A lever constructed according to my invention is simple and inexpensive in construction and both durable and efficient in operation, and the adjustments of the lever in either direction may be affected with ease, accuracy and despatch.

Having thus described my said invention, what I claim as new, and desire to secure by United States Letters Patent is:

1. In combination, a pivotally supported lever having a flexible part intermediate of its ends, a locking bar with an inner edge in an arc of a circle, a detent secured to said lever below said flexible part having opposite ends in frictional engagement with

said inner edge, and a striker plate secured to said lever above said flexible part the 30 ends of which are notched, said striker arranged to engage said detent to disengage the same, said notches engaging said detent to limit the movement of the flexed end of said lever. 35

2. In a device of the character described, a pivotally supported lever comprising a flat bar which at a point intermediate of its ends is twisted at right angles to provide a flexible part, a locking bar with an inner edge in an arc of a circle, a detent secured to said lever below said flexible part having opposite ends in frictional engagement with said inner edge, and a striker plate secured to said lever above said flexible part the 40 ends of which are notched, said striker arranged to engage said detent to disengage the same, said notches engaging said detent to limit the movement of the flexed end of said lever. 45

In testimony whereof I affix my signature, in the presence of two witnesses.

BENJAMIN H. WITHERBEE.
